United States Patent Office

Des. 232,104

Patented July 16, 1974

232,104

NEST BOX

Jacques Le Baigue, Westbury, N.Y., assignor to
Metaframe Corporation, Maywood, N.J.

Filed July 12, 1972, Ser. No. 271,025

Term of patent 14 years

Int. Cl. D30—06

U.S. Cl. D30—41

FIG. 1

FIG. 2.

FIG. 3.

FIG. 4.

FIG. 5.

FIG. 6.

FIG. 7

FIG. 8

FIG. 9

FIG. 1 is a front perspective view of a nest box, showing my new design;

FIG. 2 is a top plan view thereof;

FIG. 3 is a front elevational view thereof;

FIG. 4 is a right side elevational view;

FIG. 5 is a rear elevational view thereof;

FIG. 6 is left side elevational view;

FIG. 7 is a cross-sectional view of FIG. 3 as taken from line 7—7;

FIG. 8 is a cross-sectional view of FIG. 3 as taken from line 8—8; and

FIG. 9 is a cross-sectional view of FIG. 4 as taken from line 9—9.

I claim:

The ornamental design for a nest box, substantially as shown and described.
